BRAKING ATTACHMENT

Filed Aug. 15. 1921

2 Sheets-Sheet 2

Fig. 4.

UNITED STATES PATENT OFFICE.

JOSEPH L. DEVON, OF ATLANTA, GEORGIA.

BRAKING ATTACHMENT.

Application filed August 15, 1921. Serial No. 492,804.

To all whom it may concern:

Be it known that I, JOSEPH L. DEVON, residing at Atlanta, in the county of Fulton, State of Georgia, and a citizen of the 5 United States, have invented certain new and useful Improvements in Braking Attachments, of which the following is a specification.

The object of my invention is to provide 10 a novel braking attachment adapted more particularly for use with pumps installed on fire-engines, but which may be advantageously used in connection with any rotating shaft, and which is simple and compact 15 in construction and organization, easy to install, and reliable in operation.

The accompanying drawing shows one 20 form of embodiment of my invention capable of carrying out the underlying principles thereof, the attachment being shown in connection with a pump, of the rotary gear type, used on fire-engines. Like reference-characters denote corresponding parts throughout the several views. Briefly 25 described:

Figure 1 is a top plan view of a rotary gear pump, mounted on the frame or chassis of a fire-engine automobile or other vehicle;

30 Figure 2 is a view in end elevation, a portion of the pump being broken away and one of the members of the chassis being shown in section;

35 Figure 3 is a fragmentary detail view, partly in section and partly in elevation, of part of the braking mechanism;

40 Figure 4 is a fragmentary view in elevation of the pump with the side removed to show the gears;

45 Figure 5 is a fragmentary view, in section, on the line 5-5 of Fig. 2, the brake-band and operating mechanism therefore being removed; and

Figure 6 is a detail view of the brake-band rocker.

In the drawings, it will be understood 50 that the pump is not shown in detail, only such parts thereof being shown as are necessary to an understanding of the application of my invention thereto.

Referring, now, in detail, to the drawings:

1 designates the driving-gear of a rotary-gear pump, such as is used on "fire-engines," 55 so called, of municipal fire-departments, and 2 the driven gear thereof, mounted, re-

spectively, on shafts 3 and 4. It will be noted, by reference to Fig. 4, that, as customarily constructed, there is a considerable amount of clearance between the meshing teeth, as shown at "A." When drafting water, it is necessary, of course, to expel air from the suction pipe and suction chamber, and, sometimes, on a lift of ten feet or more, the pump fails; because, in order to discharge air from the suction faster than it will slip back into it from the discharge, the pump must be run at such speed that the gear-teeth break contact at the point "V," making an opening for air to slip back into the suction from the discharge chamber.

When this form of pump is brand new, the packing 5 is tight enough on the shaft 2 to have the effect of a brake, and so, by preventing this vibration, holds the teeth constantly in contact. However, when this packing becomes a little worn and smooth from wear, it does not grip the shaft so tightly, and then driven gear 2 breaks contact with driven-gear 1 at the point "V," and air slips back into the suction-chamber from the discharge chamber. My braking attachment prevents this, as will be apparent from a reading of the construction and operation thereof.

To adapt the pump for use in connection with my braking attachment, the driven-gear shaft 2 is extended back through the bearing retainer and dust-cap 6, and is provided with an exteriorly-projecting, reduced end 2^a. On said end is mounted a drum 7, around which passes a brake-band 8, the free ends 8', 8' of which are looped around pins 9, 9 passing through four ears 10 arranged in two pairs, one pair toward each end of a sleeve 11 rotatably mounted on a fulcrum pin 12 secured, at one end thereof, in bearings 13 detachably secured to one of the cross-braces B of the side frame-members or channel bars C, C of the chassis of the fire-engine. The sleeve 11 and the two pairs of ears 10 form part of a rocker or lever 14 having a web 15, the pin 12 constituting the fulcrum of the lever. The lever resembles, somewhat, a bell-crank lever of the conventional form, but is a modified and peculiar form thereof. Instead of one short arm, as in the conventional bell-crank lever, my lever has two pairs of short arms (the ears 10), and the ears of each pair are connected by pins 9, 9. The lower end of the

lever is pivotally secured, as at 16, to a socket member 17, having a screw-threaded socket, in which may be screwed a pull-rod 18, having a screw-threaded end 19. The 5 rod projects axially into a tubular member 20, having a pair of lateral arms 21 projecting through registering slots 22, 23 in one of the channel bars C and a wear plate 24, respectively. The wear plate is disposed 10 exteriorly of the channel bar C (as shown in Fig. 2) and suitably secured thereto.

A cam-lever 25 is fulcrumed on a pin 26 projecting through the lever and through the arms 21, 21, and has the curved cam face 15 27 bearing against the wear plate 24.

The tubular member 20 may work in the cylindrical bore of a guide-member 28.

The guide-member 28 and the wear plate 24 are secured to the channel bar C, preferably 20 by common means, such as screws 29.

One of the open ends of the tubular member 20 is exteriorly threaded, and a screw closure-cap 30 is screwed on such threaded end, and is provided with a central aperture, 25 through which the pull-rod 18 projects.

The end of the pull-rod 18 within the tubular member 20 is provided with a disk-head 31, against which one end of a coiled spring 32 bears, the other end of said spring 30 bearing against the cap 30. The spring encircles the rod 18, as shown.

It will be noted that the attachment or braking-device described is very simple and compact, and that, in operation, by pulling 35 down the lever 25, the brake-band 8 is tightened around the drum 7, thereby braking the shaft 4 of the driven gear 2. It will be noted, furthermore, that, in the operation of the lever 25, it does not pull directly on 40 the rod 18, but on the spring 32, thereby insuring uniform pressure on the brake-drum.

The lever 25 may be conveniently operated by a fireman standing on the ground beside the fire-engine, the fireman pulling the lever to apply the brake until the pump is primed and the water is being discharged. The 45 brake has then served its purpose, and should be thereupon released to prevent wear on the brake-band and drum.

Having thus fully described my invention, the many advantages thereof will be apparent, especially to those skilled in the art to which it pertains. It is obvious that many mechanical changes, especially in detail, may be made in the particular form of device disclosed; but such changes do not necessarily depart from the spirit of the invention, or sacrifice any of its advantages, and all such as come within the terms of the 55 appended claim fall within the purview of 60 the invention.

What I claim to be new and desire to secure by Letters-Patent of the United States is:

The combination with the chassis of a 65 road vehicle, said chassis including a longitudinally extending channel-bar, of a rotat- ing shaft carried by said chassis, a brake- band for said shaft, a pivoted rocker to which the free ends of said brake-band are 70 secured, a pull-rod secured to said rocker, a tubular member loosely projecting through said channel-bar and resiliently connected with said pull-rod, a hand-lever pivotally secured to said tubular member and having 75 a cam face bearing against said channel-bar, and a guide-member secured to said channel- bar and having a cylindrical bore through which said tubular member projects.

In testimony whereof I hereunto affix my 80 signature.

JOSEPH L. DEVON.
